(57) **CLAIM**

The ornamental design for a portable work deck, as shown and described.

DESCRIPTION

FIG. 1 is a front perspective view of my new design for a portable work deck. Those portions shown in broken lines are for illustrative purposes only and form no part of the claimed invention;

FIG. 2 is a top plan view of the portable work deck of FIG. 1;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.
